UNITED STATES PATENT OFFICE.

ROBERT KUHN, OF DETROIT, MICHIGAN.

ELECTRICAL SOLDERING-IRON.

SPECIFICATION forming part of Letters Patent No. 641,021, dated January 9, 1900.

Application filed January 30, 1899, Serial No. 703,818. (No model.)

To all whom it may concern:

Be it known that I, ROBERT KUHN, a citizen of the United States, residing at Detroit, in the county of Wayne, State of Michigan, 5 have invented certain new and useful Improvements in Electrical Soldering-Irons; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to electrical soldering-irons; and it consists in the construction and arrangement of parts hereinafter fully set forth, and pointed out particularly in the claims.

20 The objects of the invention are to facilitate the heating of the iron and lessen the consumption of the current by locating the resistance-coil within the working point of the tool, to provide for firmly anchoring the 25 resistance-coil within the copper point of the tool and to seal it hermetically therein, thereby lessening the liability of the burning out of the coil, and to provide for a ready removal of the point of the tool and the replacing of 30 another point, so that in case the resistance-coil becomes defective the soldering-iron may be continued in use by simply removing the old point and replacing it with a new one. These objects are attained by the construction 35 illustrated in the accompanying drawings, in which—

Figure 1 is an elevation of a complete soldering-iron involving my improved features. Fig. 2 is an enlarged longitudinal section 40 through the point of the iron, as on line 2 2 of Fig. 1, other parts being broken away. Fig. 3 is a like sectional view, as on line 3 3 of Fig. 2, the resistance-coil, with its conductor connections and the sealing-cement, being 45 omitted. Fig. 4 is a transverse section, as on line 4 4 of Fig. 2.

Referring to the letters of reference, A designates the handle of the tool, which may be of any suitable construction and through 50 which the electrical conductors *a* pass in any suitable manner.

The point B of the soldering-iron comprises a copper shell having in the upper portion thereof a cylindrical chamber *b*, which terminates at the solid part of the shell and in 55 which the resistance-coil C is located, which is of ordinary winding insulated in a manner well understood in the art, the ends of the wires of said coil being secured to the binding-screws *c c'*, which are screwed into the 60 rearwardly-projecting conducting-pins *d*, which pass through the insulating-bushings *d'*, located in the circular copper plate D, which fills the diameter of the chamber *b* in the copper shell. To support the resistance-coil centrally within said chamber, a large central pin E is employed, which is adapted to screw 65 into the solid portion of the point within said chamber and project centrally therefrom. The resistance-coil surrounds the pin E and 70 is held in place thereby through the medium of the filling of cement F, which is placed within the center of said coil around said pin, whereby the coil is maintained centrally within said chamber, so as to be free from contact with the walls thereof, as shown in Fig. 2, thereby obviating the compression of and 75 injury to the resistance-coil through a sudden contraction of the outer shell.

To hermetically seal the resistance-coil 80 within the chamber of the copper shell, a filling G of cement is placed within the outer end of said chamber upon the copper plate D and around the pins *d* and central pin E, whereby said parts are firmly retained in place 85 and the chamber in the shell so sealed as to obviate the entrance of air to the coil C, thereby decreasing the liability of the burning out of said coil.

H designates a section of the point of the 90 tool which is separated from the section B by means of the interposed layer of asbestos I, the purpose of which is to prevent the heat from the point of the iron being conducted into the handle of the tool. This section H 95 is in the shape of an inverted cup, and the center-pin E passes through said interposed layer of asbestos and into a central opening *e* in the bottom of said section H. The outer end of the pin E is provided with a V-shaped 100 groove *e'*, into which the screw *e'*, which passes diametrically through the bottom of said cup-

section, as shown in Fig. 3, is adapted to enter, whereby said section H becomes securely united to the section B.

The contact-pins *d* project into the recess 5 in said cup-section and are adapted to enter the socket-pins *f*, which project from the bottom of said cup-section in line with said pins, but which are insulated from the bottom of said section and receive the contact-screws *i*, 10 which are screwed therein and to which the conductors *a* are attached, whereby the continuity of said conductors is established through the tool to the resistance-coil C in the point thereof.

15 J designates a second layer of asbestos, which is interposed between the bottom of the cup-section H and the flanged portion K of the stem K' of the handle. This second layer of asbestos is to offer additional resistance to 20 the passage of any heat into the handle of the tool. The cup-section H is attached to the flanged portion K of the stem of the handle by means of the screws *g*, (see Fig. 3,) which pass through the bottom of said cup portion 25 and through the interposed layer of asbestos and screw into the flanged portion K of the handle.

The connection between the pins *d* and the recessed or hollow pins *f* is such that said 30 pins may be readily separated, so that upon removing the screw *e*', which engages the V-shaped groove in the end of the large center-pin E, the point B of the tool may be readily removed and a like point quickly replaced 35 and again secured in working position by

means of the screw *e*'. This arrangement requires only the changing of the point of the tool should the coil therein become burned out, thereby effecting a great saving over the ordinary construction, in which the whole tool 40 must be discarded should accident happen to the resistance-coil.

Having thus fully set forth my invention, what I claim is—

1. In an electrical soldering-iron, the combination with the handle, of the hollow point, a resistance-coil located within said hollow point, the conductors passing through the handle terminating in hollow contacts, contact-pins leading from the coil adapted to 45 enter the hollow contacts of the conductors, and means for detachably securing the hollow point with its resistance-coil to the complementary portion of the tool.

2. In an electrical soldering-iron, the combination with the handle carrying the conductors, the removable hollow point carrying the resistance-coil, detachable contacts connecting said coil with said conductors, a central pin extending from the hollow in said 55 point through said coil, and a screw passing through the side of the iron and engaging said pin.

In testimony whereof I sign this specification in the presence of two witnesses.

ROBERT KUHN.
